UNITED STATES PATENT OFFICE.

CHARLES E. BEST, OF JORDAN, NEW YORK.

ANCHOR.

SPECIFICATION forming part of Letters Patent No. 363,579, dated May 24, 1887.

Application filed March 11, 1887. Serial No. 230,807. (No model.)

To all whom it may concern:

Be it known that I, CHARLES E. BEST, of Jordan, in the county of Onondaga, in the State of New York, have invented new and 5 useful Improvements in Anchors, of which the following, taken in connection with the accompanying drawings, is a full, clear, and exact description.

The object of this invention is to provide a boat-anchor which shall have its flukes adapted to be locked in their grappling position on the shank when desired for use, and also adapted to be released from said position, so as to readily lose their anchoring hold when it is desired to 15 hoist the anchor; and to that end my invention consists in the novel construction and combination of the component parts of the anchor, as hereinafter fully described, and specifically set forth in the claims.

20 In the annexed drawings, Figure 1 is a side view of my improved anchor in its operative position. Fig. 2 is a side view of the anchor folded for storage; and Fig. 3 is a longitudinal section of the same.

25 Similar letters of reference indicate corresponding parts.

A represents the shank, which is composed of a tube having its ends screw-threaded and 30 screwed into screw-threaded sockets a a', respectively, in the ferrule or cap B and head C.

The cap B is provided with a bail, b, to which the anchor cable or chain c is attached, and is also provided with an eye, e, for the purpose hereinafter explained.

35 The head C is provided with ears d d d d, on which are hinged the flukes f f f f, said flukes having heel-extensions f' f' f' f', each of which is in line with its respective fluke, or stands in such a position in relation thereto as to cause 40 the heel-extension f' to point forward from the end of the head C and toward a point in line with the axis of the shank A.

The head C has a channel, h, extending through it in line with the aforesaid axis, and in 45 said channel slides a bolt, i, having on its inner end a head, l, which limits the outward movement of the bolt, said bolt being of sufficient length to project with its outer end between the ends of the heel-extensions f' f' f' f' of the 50 flukes when the bolt is in its extreme outward position, as represented in Figs. 1 and 3 of the

drawings. The bolt is automatically forced to its said outer position by means of a spiral spring, n, arranged in the tubular shank A, and pressing with one end on the bolt-head l and with the opposite end on a pin, o, or other suitable stop secured to the shank, as shown in Fig. 3 of the drawings. The inner end of the bolt i has attached to it a cord or thin wire, u, which is extended through the eye e of the cap B, and is of sufficient length to reach to the boat to be manipulated thereat.

The flukes when in their distended or operative position, as shown in Figs. 1 and 3 of the drawings, rest on shoulders t t on the head C, 65 and the heel-extensions of said flukes resting against the bolt i serve to lock the flukes in their said positions.

When it is desired to hoist the anchor, the same is made to readily release its grapple or 70 anchoring hold by drawing on the cord or wire u, so as to withdraw the bolt i from between the heel-extensions of the flukes, the latter being then allowed to fall forward into the position represented in Fig. 2 of the drawings, and also as shown by dotted lines in Fig. 75 3 of the drawings, and when in this position the anchor is in a compact form convenient for handling and storing.

Having described my invention, what I 80 claim as new, and desire to secure by Letters Patent, is—

1. An anchor composed of a hollow shank, a head on one end of said shank, flukes pivoted on said head and adapted to swing forward, 85 and a bolt sliding in the shank and through the head and adapted to lock the flukes in their distended position, as specified.

2. In an anchor, the combination of a hollow shank, a head secured to one end of said shank 90 and having a channel extending through it in line with the shank, flukes hinged on the head to swing forward thereon, and provided with heel-extensions, a bolt sliding in the channel of the head and adapted to enter between the 95 ends of the aforesaid heel-extensions, a spring in the shank forcing the bolt outward, and a cord or wire connected to the bolt for withdrawing the same from between the heel-extensions of the flukes, substantially as described and shown.

3. The combination of the shank A, screw-

threaded at its ends and provided with the stop *o*, the cap *B*, screwed onto one end of the shank and provided with the bail *b* and eye *e*, the head *C*, screwed onto the opposite end of the shank and provided with the channel *h*, ears *d d d*, and shoulders *t t t*, the flukes *f f f*, hinged on said ears and provided with heel-extensions *f' f' f' f'*, the bolt *i*, provided with the head *l*, the spiral spring *n*, interposed between the stop *o* and bolt-head *l*, and the cord or wire *u*, connected to the inner end of the bolt and extended through the eye *e* of the cap,

all constructed and combined substantially as described and shown.

In testimony whereof I have hereunto signed my name and affixed my seal, in the presence of two attesting witnesses, at Syracuse, in the county of Onondaga, in the State of New York, this 5th day of March, 1887.

CHARLES E. BEST. [L. S.]
